UNITED STATES PATENT OFFICE.

LUTHER A. PECKHAM, OF PROVIDENCE, RHODE ISLAND, ASSIGNOR OF ONE-HALF TO CHARLES FLETCHER, OF SAME PLACE.

FEEDING-MACHINE FOR CARDING-ENGINES.

SPECIFICATION forming part of Letters Patent No. 416,123, dated November 26, 1889.

Application filed June 10, 1889, Serial No. 313,656. (No model.)

To all whom it may concern:

Be it known that I, LUTHER A. PECKHAM, of Providence, in the county of Providence and State of Rhode Island, have invented certain new and useful Improvements in Feeding-Machines for Carding-Engines, of which the following is a full, clear, and exact description, reference being had to the accompanying drawings, forming part of this specification.

This invention relates to apparatus for supplying stock to carding machines or engines.

The objects of my invention are to improve the uniformity of the feed and to render the mechanism more efficient and positive in its operations.

My invention consists, principally, in the scale or balance and means for discharging the same, the intermittent-motion lifting-apron, means for operating the clutch on the main shaft by the scale-balancing devices, so as to connect and disconnect the driving power, and thereby start or stop the lifting-apron, the vibrating evener, and vibrating stripper; and the invention further consists in the constructional details of the various parts of the mechanism.

In order that my invention may be fully understood, I have illustrated in the accompanying drawings, and will proceed to describe, the best form thereof so far devised by me, with the knowledge, however, that such form may be variously modified without making a substantial departure from the spirit of my invention.

In the accompanying drawings, Figure 1 is a side view of my improved card-feeding device, showing the balanced levers of the balance and the gearing for revolving the scale-receptacle; also, the means for vibrating the stripper. Fig. 2 is a view of the opposite side of my improved card-feeding device, and shows the gearing and connections whereby an intermittent motion is imparted to the endless lifting-apron. Fig. 3 is a vertical section of my improved card-feeding device, showing the endless lifting-apron, the scale-receptacle, the evener, the stripper, and the movable back. Fig. 4 is an enlarged side view of a device for regulating the movement of the lifting-apron. Fig. 5 is a sectional

view, taken on the line 5 5 of Fig. 4, showing a portion of the side frame in section, as well as the lifting-apron. Fig. 6 is a side view of the latch device for locking the upper end of the rod connecting with the clutch, and also the knock-off cam and the device for operating the latch to release the upper end of the rod. Fig. 7 is a top view of the latch device and latch-releasing device. Fig. 8 is a front view of the evener, showing the method of adjusting the blades provided with teeth; and Fig. 9 shows another way of supporting and operating the evener. Fig. 9^a is a sectional view of part of the lifting-apron.

In the said drawings like numbers of reference designate corresponding parts throughout.

Referring to the drawings, the number 10 designates the sides of the case for holding the fibrous stock and on which are mounted in suitable bearings the various parts of the mechanism. The endless lifting-apron 11 passes about the rollers 12 12^a, and receives its motion from the drive-shaft 13, passing through the top roller 12^a, the apron traveling upward, as indicated by the arrow in Fig. 3 of the drawings. The two rollers 14 15 are placed on the inside of the endless apron to relieve the strain on the apron by reason of the force exerted by the movable back in holding the stock against the apron. The movable back is made in two parts, the inner part 16 being supported on suitable brackets or side pieces 17, secured to the outer portion 18. In Fig. 3 the inner part of the back is shown as being pivoted to the bracket at 19, the top portion of the bracket forming a stop to prevent the top of the inner back being pushed backward. The spring 20 is secured in a suitable holding device near the bottom of the bracket and in contact with the lower portion of the back 16, thereby allowing a slight backward movement of the same, so as to relieve it from any unusual strain that might be brought to bear against it.

The evener 21 is provided with the semi-circular guard 28, which forms a movable continuation of the fixed top piece 29, and is supported on and reciprocates with the cross-bar 30, forming part of the evener. The evener is also provided with an adjustable

comb. A front view of the comb and part of the evener is shown in Fig. 8 of the drawings, in which it is seen that the comb is made in two parts. The plates 23, carrying the teeth 22 and forming the comb, are provided with the slots 24, through which the bolts 25 pass, so that the comb may be readily adjusted by loosening the bolts 25, then lifting or lowering the plates 22, and then tightening the bolts 25 to securely hold the plates in the desired position.

In the preferred form of construction—that is, the form illustrated in Figs. 1, 2, and 3—the evener is shown as supported and having movement in the slots 26, one being formed in each of the side frames 10 10. A reciprocating movement is imparted to the evener 21 from the main shaft 31 through the gear 32, intermediate gear 33, gear 34, shaft 35, bevel-gear 36, bevel-gear 37, shaft 38, bevel-gear 39, and bevel-gear 40, secured to shaft 41, carrying the two disks 42 42, one on each end. The adjustable links 43 43 are pivotally connected to the cross-bar 30 at one end and to the bearing-bolts 44 44, adjustably secured in the slots 45 45, formed in the disks 42 42. The comb of the evener extends across the path of the apron, and when vibrated it moves so as to sweep over the top portion of the apron and comb and even the stock off, so that it may be properly fed to the stripper.

The clearer 46 extends across the receptacle from one side to the other, and is provided on its upper side with the teeth 47. The object of the clearer is to remove from the teeth of the evener any of the stock that might cling thereto and in turn to be cleared from any adhering fiber by the teeth of the evener.

The endless lifting-apron 11 receives its movement through the ratchet-gear 48, provided with the outwardly-extending hub and secured to the shaft 13 by a spline 49. Mounted upon the hub of the gear 48 is the segmental rack 50, provided with the spring-pressed L-shaped pawl 51, one arm of which extends outwardly and rides on or over the top surface of the cam 52. The cam 52 is loosely mounted on the shaft 13, and extends outwardly therefrom, and is provided with the loosely-pivoted pawl 53, and the spring-pressed bolt 54 for holding the pawl 53 against the ratchet-gear 48, and has the handle 55 for lifting or lowering the cam, so that the outwardly-extending finger of the pawl 51 will ride a longer or shorter distance on the cam-surface. The bolt 56 passes through the semi-circular slot 57, formed in the outwardly-extending portion, and serves to hold the cam in the desired position. It will be readily seen that as the ratchet-gear 48 is securely held to the shaft carrying the top roller, over which the apron 11 moves, the movement of the apron will depend upon the movement of the ratchet-gear, and consequently upon the number of teeth the pawl 51 will take up. The largest movement of the apron is ob-

tained by loosening the bolt 56 and depressing the handle 55 to its lowest point, when the cam-surface will be entirely removed from contact with the outwardly-extending finger of the pawl 51, and consequently the pawl will, upon being reciprocated, take up the largest number of teeth of the ratchet-gear 48, and consequently move the apron the greatest distance, whereas if the handle be lifted to its highest point the cam-surface will be brought forward and the outwardly-extending finger of the pawl 51 will ride on it and engage with the smallest number of teeth of the ratchet-gear 48, and the apron will be lifted the shortest distance. It is therefore evident that the cam-surface can be so set as to give just the desired amount of lift to the apron, the variation in the lift of the apron depending upon the quality and quantity of stock used.

The vibrating stripper 58 is provided with the comb 59, lying across the path of the apron, and the stripper is mounted upon the rocking shaft 60, which is rocked by the sector-gear 61 secured thereto, which gear receives an oscillating motion from reciprocating mechanism hereinafter described. This stripper is also provided with the adjustable brush 62, which is held in position and is adjusted by the bolts 63 and 64. The stripper sweeps over a portion of the apron and across the catch-shelf 65, which is slightly curved, with the concave face lying upwardly, and upon which are placed the comb-teeth 72. Upon each longitudinal edge of the shelf is disposed a toothed blade 73. The vibrating stripper 58 and the evener 21 are located at the upper end of the apron and are operated simultaneously to even the fiber and strip the same from the apron.

An intermittent motion is imparted to the apron 11 by means of the following mechanism: Upon the drive-shaft 31 is mounted the gear 32, intermeshing with the intermediate gear 33, which intermeshes with the gear 34, mounted on the shaft 35 and provided with the slot 66, in which is secured the bearing-pin 67. One end of the connecting-rod 68 is pivotally secured to the bearing-pin 67, the other end being secured to the bearing-pin 69, mounted on the sector-gear 70, which intermeshes with the gear 71, intermeshing with the rack 50, carrying the pawl 51, which pawl operates the ratchet-gear 48 and imparts intermittent motion to the apron 11. The gear 71, also intermeshing with the sector-gear 61, will at the same time impart reciprocating motion to the stripper 58.

The scale or balance and the discharging mechanism for the same consist of the following parts: The receptacle formed with the two circular end plates 74, one at each end, the division-plates 75, abutting against the end plates and strengthened by the arms 76, the whole being attached to and supported on the shaft 77, which extends through the two side frames 10 10, and is connected at one side to

the balanced lever 78 by the link 79, which is pivoted to the lever 78 at one end and supports the end of the shaft 77 in a suitable bearing at the other end. The lever 78 is pivoted on the fixed pin 80. The two rods 81 and 82 extend from the lever 78 to the lever 83, thereby causing both the levers to move together. The lever 83 is pivoted on the fixed pin 84 and carries the weight 85, a similar weight being carried by the lever 78. The free end of the lever 83 is connected to the lever 86 by the strap 87. This lever 86 is pivoted to the bracket 88, and carries a weight 89 and latch-releasing device consisting of the sliding rod 90, which is held in normal position by the spring 90^a, and carries the outwardly-extending adjustable pin 93 and the upwardly-extending finger 91, which finger 91 is acted on by the cam 92, attached to one end of the shaft 60, to force the pin 93 against the beveled upright fingers of the latch 94, thus releasing the upper end of the rod 95 and allowing the same to drop, and, through the bell-crank 96, release the friction-clutch 97 and stop the entire operation of the feed. The friction-clutch 97 may be of any of the ordinary and well-known forms of friction-clutches. The latch 94 is supported on the bracket 104, and is held closed by the spring 105, one end of which is held by the pin secured to the bracket and the other end by the pin which passes through a slot in the bracket, and is fastened to the latch, as clearly shown in Figs. 1 and 6 of the drawings. The vertical support-bar 98 is pivoted to the balanced lever 83 at 99 and supports the end of the shaft 77, provided with the gear 100, and carries the intermediate gear 101 and the gear 102 on suitable bearings, and is held against sidewise movement by the link 103. The gear 102 is provided with a number of pins 106.

One side of the receptacle (in position in Fig. 3) is formed by the division-plates 75, and the other side by the swinging plate 107, which is hinged to the under side of the catch-shelf 65, the bottom being always formed by one of the division-plates 75 and the ends by the circular ends of the rotary scale. The corrugated presser-roller 111 is supported over the endless delivery-apron 108, which passes over the rollers 109 110. The presser-board 112 is pivoted at the top, one of the pivots extending through the side frame 10, and has the L-shaped lever 113 secured to it. One arm of the lever 113 carries the weight 114. To the lower end of the other arm is attached the link 115, carrying a friction-roller at its free end. The cam 116 is mounted on the shaft 117, and operates against the friction-roller so as to swing the presser-board outward, the weight 114 returning the presser-board to the normal position as soon as the curved face of the cam has passed. The gear 118 is secured to the shaft 117 on the same side as the cam 116 and intermeshes with the gear 119, secured to the

shaft of the presser-roll 111, thereby causing the presser-roll to be revolved when power is applied. On the opposite end of the shaft 70 117 is secured the gear 120. This gear carries two sets of pins. One set 121, on the inside, comes in contact with the end of the support-bar 98 and lifts the same, and with it the balance and receptacle, into the normal 75 position. The other set of pins 122, on the outside of the gear 120, serves to lift the clutch-operating rod 95 into normal position by coming in contact with the lower surface of the cam-finger 123, which is secured to the 80 bar 95. The wiper-bar 124 is secured to the shaft 117 outside of the gear 120, and carries at its ends the adjustable fingers 125 125, the fingers 125 being adjustably secured to the wiper-bar 124 by the screws 126 126, which 85 pass through the slots 127 127, formed near the ends of the wiper-bar.

The delivery-apron 108, the presser-roll 111, the cam 116, the gear 120, and the wiper-bar 124 are operated from the gear 128, which is 90 driven by the gear 129, which gear is attached to one of the revolving shafts of the carding-engine at its receiving end. The gear 128 intermeshes with the gear 130, secured to the shaft of the roller 110, and operates the delivery-apron 108. The gear 128 also intermeshes with the gear 120, causing the shaft 117 to revolve, and with it the wiper-bar 124, the cam 116, and the gear 118, which gear 118 intermeshes with the gear 119, mounted 95 on the shaft of the presser-roll 111, thereby causing the roll to revolve and compress the stock as the same is carried to the carding-engine by the delivery-apron 108. The back 18 is secured to the shaft 131, which extends 100 through the side frames 10 10 and is provided with the sector-gears 132 132 at each end, into which the sector-gears 133 133, formed on the ends of the weight-rods 134, intermesh. The weights 135 135 are moved outwardly 110 until the weight of the back will be slightly overcome, when the back will be caused to keep a constant pressure on the stock and force the same against the lifting-apron 11. In some instances it may be desirable to automatically adjust the cam 52 as the back 18 moves inward, so as to cause the lifting-apron 11 to move a longer distance and consequently lift a larger quantity of stock. In such a case all that is required is to connect 115 the handle 55, forming part of the cam device, by the rod 136 to the weight-rod 134, by means of the adjustable collar 137, (the rod 136 and collar 137 are shown in broken lines in Fig. 2 of the drawings,) when, as the weight-rod descends, the cam-surface will be carried 120 backward, allowing the pawl 51 to take up a larger number of the teeth of the ratchet-gear 48, and consequently lift the apron 11 a greater distance. The bevel-faced notch 138 125 is cut in the side of the vertical support-bar 98, and the spring-pressed catch 139, having a beveled face, is secured to the side frame 10, so that as the vertical support-bar 98 starts 130

to descend the catch will enter the notch and assist in forcing the vertical support-bar downward and also hold the same against any rebound, the catch 139 acting as a spring-pressed bolt having a beveled or pointed end, which enters the V-shaped notch 138 on the edge of the bar 98. As this latching device is only a refinement which may be dispensed with, no detailed drawing of the same has 10 been made.

From the foregoing the following description of the operation of the mechanism will be readily understood. As the wool or other stock is lifted by the apron 11 from the receptacle formed by the sides 10 10 and back 18, which latter keeps a constant pressure on the stock, forcing the same against the apron and approaches the top, the vibrating evener 21 sweeps backward over it and combs and evens 15 the wool or other stock off, so that it may be properly fed to the delivery side of the apron. The wool is then stripped from the apron by the comb and brush of the vibrating stripper 58, it being swept across the catch-shelf 65 20 and carried off the same by the motion of the stripper. After leaving the shelf 65 the wool falls into the receptacle of the scales formed by two of the partition-plates 75, the hinged plate 107, and the circular ends. Upon a pre-determined quantity or weight of stock having 25 been swept into the scale-receptacle by the stripper 58, the weights 85, supported on the balanced levers 78 and 83, will be overbalanced and the scale will descend, and with 30 it the vertical support-bar 98, causing the weighted end of the balanced lever 86 to be lifted up until the finger 91 is brought into the path of the vibrating cam 92, causing the bar 90 to be moved and the pin 93 to be 35 brought into contact with the beveled finger of the latch 94, thus releasing the clutch-rod 95 and allowing the same to fall and disengage the clutch from the power-pulley 140 and stopping the machine. At the same time that 40 the machine has been stopped and the scale has reached its lowest point the wiper-bar 124 has assumed the position shown in broken lines in Fig. 1, and will soon be brought into contact with one of the pins 106, revolving the gear 102, the intermediate gear 101, and the gear 100, and with it the shaft 77, turning the scale-receptacle down and allowing the contents to drop on the delivery-apron 108. The pin 121 on the gear 120, following closely on 45 the movement of the wiper-bar 124, will be brought into contact with the lower end of the vertical support-bar 98, and will lift the same and the scale into their normal positions. The pin 122, following directly after 50 the pin 121, will come in contact with the cam-finger 123, thereby lifting the rod 95 and forcing the clutch 97 into contact with the power-pulley 140 and starting the machine. The foregoing operations will be repeated, 55 and as the quantity of stock held between the apron and the back decreases more stock may be supplied by pulling the back outward and

placing the stock between the two parts 16 and 18 of the back.

An important feature of this invention consists in a casing 145, which completely surrounds and protects all of the working parts of the scale mechanism. The casing 145 is secured to one of the side frames and has an opening for the link 79 to pass through, and on the other side frame of the feed is secured the casing 145, which is open at the bottom and has an opening on one side for the link 103 to pass through, as clearly shown in Fig. 1 of the drawings. The sides of the boxes or cases are shown in section projecting from the frames. The ends opposite the frame are closed by plates or covers secured against the projecting sides of the casings 145 and 146, so as to form closed boxes provided only with 75 the openings heretofore mentioned. It will be seen that by thus inclosing all the parts of the scale mechanism they will be protected from flying dust or fiber; also, that the machine may be wiped or cleaned, without in 80 any manner interfering with the balanced levers of the scale mechanism, while the feed is in full operation.

I prefer to construct the lifting-apron with the double slats 146 147, so that the pins 148 95 will be passed through the outer slat 146, and the inner slat 147 will act as a backing to prevent the pins being forced back through the webbing 149, forming the apron proper.

In some instances it is desirable to place 100 the springs 141 onto the frame to assist the back in maintaining its pressure against the stock; but in all ordinary cases I find the weights 135 sufficient. It may also be found preferable to support the evener in the manner shown in Fig. 9 of the drawings, in which the evener 21 is hung by the arms 142 to a shaft supported in the brackets 143, one bracket being mounted on top of each of the side frames 10 10. The arms 144 are also secured to said shaft, and by reason of their connection with the rods 43 reciprocating motion will be imparted to the evener.

Having thus described my invention, I claim as new and desire to secure by Letters Patent— 115

1. The combination, as hereinbefore set forth, with a lifting-apron, of a two-part back hinged at the base thereof, capable of moving toward and away from the apron, and forming the back of the stock-receptacle, and a lever, substantially as described, for rocking said back toward the apron.

2. In an apparatus for feeding fibrous material, the combination, with the stock-receptacle and the lifting-apron, of a two-part back, 125 the inner portion being pivoted on the side brackets, forming part of the outer portion, the whole forming the back of the stock-receptacle, substantially as herein set forth.

3. In an apparatus for feeding fibrous material, the combination, with the main shaft, the lifting-apron, and its drive-shaft, of the gears 32 33 34, connecting-rod 68, sector-gear 70, gear 71, rack 50, pawl 51, cam 52, and

ratchet-gear 48, whereby the apron may be run with an intermittent motion, substantially as and for the purpose herein described.

4. In an apparatus for feeding fibrous material, the combination, with the lifting-apron and its drive-shaft, of a ratchet-gear secured to the said drive-shaft, a rack carrying a pawl which engages with the teeth of the said ratchet-gear, mechanism for actuating the rack, and a cam, substantially as herein shown, for lifting the pawl above the line of the ratchet-gear teeth, as and for the purpose herein shown.

5. In an apparatus for feeding fibrous material, the combination, with the stock-receptacle and the lifting-apron, of a scale consisting of a rotating receiver divided by partitions into receptacles and supported by two balanced levers, and suitable gearing, whereby the scale-receptacle may be partially revolved, substantially as herein shown and described.

6. In an apparatus for feeding fibrous material, the combination, with the stock-receptacle, of the two-part back, the reciprocating evener, the intermittent-motion lifting-apron, the vibrating stripper, the scale-receptacle supported on the pivoted balanced levers, the rod 90, spring 105, lever 86, and strap 87, the shipper-bar, the latch for locking the upper end of the shipper-bar, the latch-releasing device consisting of the finger and pin and the cam, and mechanism, substantially as herein shown, for revolving the scale-receptacle and for lifting the shipper-bar.

7. In an apparatus for feeding fibrous material, a back consisting of the inner portion 16, the side brackets 17 17, the outer portion 18, the shaft 131, the gears 132, the gears 133, the weight-rods 134, and the weight 135, substantially as herein shown.

8. In an apparatus for feeding fibrous material, the combination, as herein set forth, of the end pieces 74, the division-plates 75, the shaft 77, with the levers 78 and 83, the link 79, the support-bar 98, the gears 100, 101, and 102, and the pins 106, the wiper-fingers 125, and wiper-bar 124, constructed to partially rotate the scale-receptacle, as described.

9. The combination, in an apparatus for feeding fibrous material, of the driving-pulley 140, clutch 97, the bell-crank 96, clutch-bar 95, latch 94, balanced lever 86, carrying the sliding rod 90, provided with the finger 91 and pin 93, the cam 92, whereby the latch 94 is caused to release the clutch-bar 95 upon the free end of the balanced lever 86 being lifted by the scale mechanism, substantially as and for the purpose herein described.

10. The combination, in an apparatus for feeding fibrous material, of the stock-receptacle, the intermittent-motion lifting-apron

11, the evener 21, provided with the adjustable comb 23, rods 43, disks 42, shaft 41,

bevel-gears 40 and 39, shaft 38, bevel-gears 37 and 36, shaft 35, gears 34, 33, and 32, and shaft 31, whereby reciprocating motion is conveyed to the evener 21, substantially as herein shown and described.

11. The combination, in an apparatus for feeding fibrous material, of the two-part back supported on the shaft 131, the lifting-apron 11, the rollers 14 15, cleaver 46, evener 21, provided with the comb 23, mechanism, substantially as herein shown, for conveying reciprocating motion to the evener, the vibrating stripper 58, mounted on shaft 60 and provided with the comb 59 and brush 62, sector-gear 61, gear 71, sector-gear 70, connecting-rod 68, and gears 34, 33, and 32, whereby the stripper is caused to vibrate across the path of the lifting-apron, substantially as and for the purpose herein shown and described.

12. The combination, in an apparatus for feeding fibrous material, with the stock-receptacle, the intermittent-motion lifting-apron, the reciprocating evener, the vibrating stripper, the scale-receptacle and balance mechanism, the delivery-apron, the presser-board and the presser-roll, of the gear 128, gear 130, for driving the delivery-apron, gear 120, the shaft 117, the gear 118, for driving the gear 119 and with it the presser-roll, the cam 116, link 115, and arm 113, for moving the presser-board 112 outward by means of the link 115 and arm 113, substantially as herein shown and described.

13. The combination, with the stock-receptacle, the lifting-apron, the reciprocating evener, the vibrating stripper, the scale-receptacle and balance mechanism provided with the support-bar 98, the clutch-bar 95, and cam-finger 123, of the gear 129, the gear 128, and gear 120, carrying the pins 121 and 122, for lifting the scale-receptacle to its normal position through the support-bar 98, and the clutch-bar through the cam-finger 123, substantially as herein described.

14. The combination, with the stock-receptacle, the lifting-apron, the reciprocating evener, the vibrating stripper, the scale-receptacle, and balance mechanism provided with the gears 100, 101, and 102, of the gear 128, gear 120, shaft 117, and the wiper-bar 124, whereby the scale-receptacle is revolved through the gears 102, 101, and 100, substantially as herein shown and described.

15. In an apparatus for feeding fibrous material, the combination of the stock-receptacle and a lifting-apron composed of a webbing 149, slats 146, pins 148, and slats 147, as described.

In witness whereof I have hereunto set my hand.

LUTHER A. PECKHAM.
